UNITED STATES PATENT OFFICE.

JOHN L. BROWN, OF MINNEAPOLIS, MINNESOTA.

PORTABLE BATH-HOUSE.

1,254,771.

Specification of Letters Patent. Patented Jan. 29, 1918.

Application filed December 1, 1916. Serial No. 134,392.

To all whom it may concern:

Be it known that I, JOHN L. BROWN, a citizen of the United States, residing at Minneapolis, in the county of Hennepin 5 and State of Minnesota, have invented certain new and useful Improvements in Portable Bath-Houses; and I do declare the following to be a full, clear, and exact description of the invention, such as will enable 10 others skilled in the art to which it appertains to make and use the same.

This invention relates to new and useful improvements in portable booths or screens adapted for use as bath houses, which are 15 foldable so that when not in use they may be knocked down and easily transported.

Another object of the invention is to provide a device of this character which is equipped with a collapsible head comprising 20 a plurality of curtain or cover supporting arms projecting radially therefrom, and which are foldable and adapted to swing down to a position parallel with the support, when not in use.

Still another object of this invention is to provide a device of this character which is simple and durable in construction, inexpensive to manufacture, and one which will be very efficient in operation.

With these and numerous other objects in view, the invention consists of the novel features of construction, combination and arrangement of parts which will be herein referred to and more particularly pointed out 35 in the specification and claims.

In the accompanying drawings:

Figure 1 is a side elevation of the standard showing the cover secured thereto with one side removed;

Fig. 2 is a plan view of the device with the base and adjusting means not shown, so as to illustrate the position of the arms and upper edge of the cover more clearly;

Fig. 3 is a detail side view of the upper 45 end of the standard showing the bracket with the arms horizontally disposed;

Fig. 4 is an end view of the bracket showing the same in position similar to that shown in Fig. 3;

Fig. 5 is a plan view of this portion of the standard;

Fig. 6 is a horizontal section on the line 6—6 of Fig. 3;

Fig. 7 is a view of the device in folded 55 position, with the cover removed, and for

the sake of clearness, I have removed the spring therefrom; and

Fig. 8 is a detail perspective showing the upper edge of the removable cover and the manner in which it is positioned when 60 placed around the standard.

In describing my invention I shall refer to the drawings in which similar reference characters designate corresponding parts throughout the several views and in which 65 the numeral 1 designates the supporting standard employed in this device, which is made longitudinally adjustable, by forming the same of two sections, a lower section 2 and an upper section 3, which are slidably 70 connected with each other as shown at 4, and adjustable by a spring bolt 5 as clearly shown in Fig. 1 of the drawings. The upper section 3 is provided with a plurality 75 of openings 6 in which the end of the spring bolt may be positioned according to the adjustment desired for the standard.

This standard 1 is provided at its lower end with a plurality of foldable legs 7 which form a supporting base for the same when 80 in open position. These legs are of any conventional shape, it being merely necessary that they fold in such a manner that they will be disposed substantially in alignment with the standard when the device is 85 knocked down. Preferably they are hinged at their upper ends as shown at 8 with the inclined extremities 9 so arranged that they will be positioned against the adjacent sides of the standard when the legs are opened. 90 When closed they will fold inwardly and be disposed substantially parallel with respect to the standard as clearly shown in Fig. 7 of the drawings.

Mounted on the upper end of the standard 95 1 is a substantially U-shaped bracket 10 which is rotatably mounted on a horizontally extending pivot 11 which projects through said standard and is held in position thereon by a nut 12 on its outer end. 100 This bracket 10 is adapted to swing vertically, its movement in one direction being limited by a stop 13 projecting from the adjacent side of the standard, and when in this position it may be locked by means of 105 a lock button 14 pivotally mounted on the opposite side of the standard, and which is adapted to be swung outwardly therefrom in the path of movement of the bracket.

Between the sides of the bracket 10 are 110

secured pivot rods 15 which are disposed on an inclined plane, and which are adapted to have mounted thereon two pairs of arms 16 and 17 respectively. The outer arms 17 are of equal length, and the inner arms 16 are similarly positioned, but owing to the fact that the rods 15 upon which they are mounted are disposed at an angle, the extremities of the arms will be of different lengths accordingly. These arms are adapted to swing freely upon the pivots for a purpose to be hereinafter more fully described. When the bracket 10 is disposed as shown in Fig. 7 of the drawings, the pairs of arms 16 and 17 will hang downwardly in substantially parallel relation with each other and will be disposed parallel with the standard 1. When it is desired to open the device, the bracket 10 is swung so that the arms will be disposed horizontally, and when in this position the operation of the lock button 14 will hold the bracket so that the arms will be unable to swing back to their first position. The arms are then swung 25 outwardly to various radially spaced positions as clearly shown in Figs. 1 and 2 of the drawings, whereupon the collapsible head will be opened.

To securely hold the arms in position I have provided a coiled spring 18 which is secured at its opposite ends to the outer surfaces of the arms 17, intermediate their ends, and which when the arms are opened and swung outwardly to the position shown 35 in Fig. 2 of the drawings, will exert a constant tension on the same to hold them in this relation. This spring 18 will be stretched between the two outside arms, and will be positioned at the back of the side 40 of the standard opposite to which the bracket is secured and will tend to draw the arms toward each other, consequently holding them permanently in position. The intermediate arms 16 are steadied in open position by means of a cord 19 which has its opposite ends secured to the inner faces of the arms 16 and which extends through openings 20 in the arms 17 in substantially 45 rectangular form as clearly shown in Fig. 50 2 of the drawings. This cord is drawn taut when the arms are open and will consequently steady the same.

When the arms are in open position they are adapted to hold thereon a removable cover 21 formed of canvas or any other desired material which is positioned around the standard and has its downwardly extending sides reaching to the ground. This cover 21 has one end or edge thereof connected to the standard as shown at 22, and the said cover extends around the standard and has its opposite edge brought back and likewise secured over the first mentioned edge. When in operation these two edges 65 may be drawn apart to afford an entrance to

the bath house. The cover is preferably formed of canvas or like material, and is provided at the corners of its upper edge with hooks 23 which engage openings 24 adjacent the extremities of the arms 16 and 17. 70

The object of providing a portable bath house of this character is to provide a booth or screen wherein swimmers or bathers can dress or undress at lakes and streams where no public or private bath houses are maintained. This house may be folded up so as to occupy a very small space, whereby it may be easily carried, or strapped to the running board of an automobile, etc. 75

To erect the bath house it is only necessary to position the standard perpendicularly and raise it a short distance from the ground whereby the legs will spread out by gravity, forming a base or support for the standard. Next the spring bolt is withdrawn and the upper section of the standard is lifted to the desired height, whereby the bolt will drop back in place and lock it at this point. 80

The arms 16 and 17 are then grasped and raised from a vertical to a horizontal position, then given a one-half turn to the right, thus turning the vertically pivoted bracket, and the bracket is then locked in position by turning the lock button. The arms are 90 then swung to the various radial spaced positions as clearly shown in Fig. 2 of the drawings, and the coiled spring is swung up over the standard and back of the same until it holds the arms extended in a manner hereinbefore fully described. The removable cover is then placed around the projecting arms and hooked thereon at the extremities of the same. The adjacent overlapping ends of the cover will be disposed at 100 the back of the standard whereby easy access may be had to the completed house. 105

The projecting arms may be formed of channel iron, to give them the required strength and stability. The cord passed 110 through these arms will steady them in position and the coiled spring will securely hold them open as long as desired.

From the foregoing description of the construction and operation of my improved portable bath house, the manner of applying the same to use, and the operation thereof will be readily understood, and it will be seen that I have provided a simple and efficient device of this character for carrying 115 out the objects of the invention. 120

I claim:

1. A device of the character described comprising a longitudinally adjustable vertically disposed standard having a foldable 125 base at its lower end and a collapsible head at its upper end, a plurality of radially positioned arms on said head adapted to be disposed in operative position in a horizontal plane to one side of the standard, said arms 130

in inoperative position being disposed in parallel relation, said head being adapted to fold to parallel relation with the standard in closed position and a removable curtain supported by said arms.

2. A device of the character described comprising a longitudinally adjustable vertically disposed standard having a folding base, a bolt extending through said standard near the top thereof, a substantially U-shaped bracket rotatably mounted on said bolt and adapted to be positioned at one side of said standard, locking means positioned on said standard to hold said bracket in vertical position, a plurality of arms pivoted on said bracket and adapted to swing to various radial positions when the bracket is horizontally disposed, means for holding said arms in spaced relation when radially disposed and a removable curtain supported on said arms.

3. A device of the character described comprising a vertical standard having a horizontally disposed aperture adjacent the top thereof, a horizontally extending pivot in said aperture, a substantially U-shaped bracket having a pair of spaced arms rotatably mounted on said pivot, a plurality of pivot rods positioned between said arms, a plurality of radially projecting arms formed of single sheets of metal having their outer ends bent in the form of eyes for engagement with the pivot rods and a curtain supported on the end of said arms.

In testimony whereof I have hereunto set my hand in the presence of two subscribing witnesses.

JOHN L. BROWN.
